UNITED STATES PATENT OFFICE

2,609,820

CIGAR AND CIGARETTE HOLDER

Randey Vakilian, New York, N. Y.

Application May 6, 1949, Serial No. 91,756

1 Claim. (Cl. 131—175)

1

This invention relates to cigar and cigarette holders, and has for one of its objects the production of a simple and efficient means for entirely enclosing a smoking article, such as a cigar and cigarette, within a casing, thereby protecting the smoking article as well as other objects which may be adjacent thereto.

A further object of this invention is the production of a cigar and cigarette holder which comprises an apertured casing to permit a draft to pass through the holder, and includes means for closing the apertures in the casing to extinguish the smoking article by cutting off the draft, so that the holder may be carried in a pocket without the possibility of burning the clothing, and at the same time preserve the smoking article for subsequent relighting, and thereby prevent waste.

Other objects and advantages of the present invention will appear throughout the following specification and claim.

In the drawing:

Figure 1 is a side elevational view of the cigar and cigarette holder constructed in accordance with my invention;

Figure 2 is an enlarged fragmentary longitudinal sectional view of the holder, certain parts being shown in elevation;

Figure 3 is a transverse sectional view taken on line 3—3 of Figure 2;

Figure 4 is a perspective view of the holder showing the inner and outer casings in a partly open position without the conventional mouth-piece;

Figure 5 is a fragmentary sectional view of the inner and outer casings.

By referring to the drawing, it will be seen that 10 designates the conventional mouth-piece which is provided with a socket 11 into which the inner end 12 of the inner tubular casing 13 is adapted to fit. The inner casing 13 is provided with an aperture 14 through which aperture 14 the inner end of a cigarette or cigar 15 is adapted to extend, as shown in Figures 2 and 3. The cigarette or cigar also is adapted to extend into the cigarette or cigar receiving socket in the mouth-piece 10, as shown in Figure 2. The casing 13 is in the nature of a tube having longitudinally extending radially spaced vent slots 16. An enlarged cigarette receiving slot 17 is formed in the inner casing 13, upon one side thereof, as shown in Figure 4. A bayonet slot 18 also is formed in the inner casing 13 and comprises a longitudinally extending portion terminating in a transverse portion 19 at the inner end of the casing 13.

2

An outer tubular casing 20 is slidably mounted upon the inner casing 13 and is provided with an outer closed end 21. The outer casing 20 is provided with a plurality of longitudinally extending radially spaced vent slots 22 which are adapted to register with the slots 16 and 17 formed in the inner casing 13. A retaining pin 23 is carried by the outer casing 20 and extends into the bayonet slot 18 of the inner casing 13. The outer casing 20 is adapted to be moved longitudinally of the casing 13, which casing 13 telescopes into the outer casing 20, as shown in Figure 4. The outer casing 20 is adapted to be moved to an extended position relative to the inner casing 13 for a distance sufficient to permit a cigarette or cigar to be dropped through the slot 17 into the inner casing 13. One end of the cigarette 15 is then extended through the aperture 14, as shown in Figure 4. The outer casing 20 is then closed over the inner casing 13 by moving the casing 20 longitudinally of the casing 13. The casing 20 is then rotated upon the casing 13. The pin 23 slides from the longitudinal portion of the slot 18 into the transverse portion 19 of the bayonet slot 18 to lock the outer casing 20 against longitudinal movement upon the inner casing 13 until the casing 20 is again rotated in the opposite direction to bring the pins 23 into registration with the longitudinal portion of the slot 18. The transverse portion 19 of the slot 18 is sufficiently long to permit the outer casing 20 to be rotated upon the inner casing 13 to and from a position to move the slots 22 into and out of registration with the slots 16 and 17 of the inner casing 13 to open and close the vents. When the slots are closed the holder will be rendered absolutely fire-proof.

When the outer casing 20 is moved to an extended position to fully open the slot 17, and the holder is held so as to position that portion of the inner casing 13 intermediate the vent slots 16 below the used cigarette, this intermediate portion will provide an ash-receiving means upon which ashes from the cigarette may drop until the ashes are dumped into an ash tray or the like.

When the casings 13 and 20 are used with the mouth-piece 10, the outer casing 20 extends flush with the outer face of the mouth-piece 10, as shown in Figure 2. However, the device may be used in a manner to dispense with the mouth-piece 10 if desired, in which event one end of the cigarette 15 protrudes through the aperture 14, as shown in Figure 4. The outer casing 20 is then closed over the inner casing 13, when the device is used in this manner, as previously described.

By means of a device above described and illustrated in the accompanying drawing, it will be seen that a very simple and efficient means has been provided whereby the cigarette may be extinguished owing to the deprivation of air and at the same time prevent ashes from falling through the apertures of the casing whereby the holder may be carried in the pocket of the user without possibility of damage to the clothing.

While I have illustrated and described my invention with some degree of particularity, I realize that in practice various alterations thereover may be made, and I, therefore, desire to reserve the right and privilege of changing the form of the details of construction, or otherwise altering the arrangement of the correlated parts without departing from the spirit of the invention or the scope of the appended claim.

What I claim as new is:

A holder for a smoking article comprising an inner casing having a smoking article receiving aperture at one end thereof, said inner casing having an enlarged cigarette receiving slot upon one side thereof for facilitating the placing of a cigarette longitudinally of and within the inner casing and then into the aperture at one end of the inner casing, said inner casing also having longitudinally extending radially spaced vent slots, said inner casing having a bayonet slot formed therein and comprising a longitudinally extending portion terminating in a transverse portion at the inner end of the inner casing and terminating short of the opposite end of the casing, an outer tubular casing slidably mounted upon the inner casing and provided with a closed outer end, said outer casing having longitudinally extending radially spaced vent slots adapted to be brought into registration with the vent slots of the inner casing, a pin fixed to and carried by the outer casing and slidably engaging said bayonet slot which is formed in said inner casing

and holding the outer casing against accidental removal from said inner casing, the outer casing being rotatable for a limited distance upon the inner casing to open and close the vent slots, the inner casing having relatively wide portions intermediate the vent slots, the pin being movable in the transverse portion of the bayonet slot as the outer casing is rotated upon the inner casing, and the pin being movable longitudinally of the longitudinal portion of the bayonet slot as the outer casing is moved longitudinally of the inner casing, the longitudinal movement of the outer casing outwardly of the inner casing uncovering the enlarged cigarette receiving slot for substantially its entire length to provide for the removal of a cigarette from the inner casing by the fingers of a user, while the portion of the inner casing intermediate the vent slots thereof constitutes an ash receiving means should ashes drop from the cigarette while the used cigarette is being removed from the holder.

RANDEY VAKILIAN.
